UNITED STATES PATENT OFFICE

ARCHIE CARL COOPER, OF HURON, SOUTH DAKOTA

DOOR HOLDER

Application filed November 4, 1927. Serial No. 231,071.

This invention aims to provide a simple means whereby the doors of garages, or closures of any other kind whatsoever, may be operated conveniently, to move them to and from a closed position.

It is within the province of the disclosure to improve generally and to enhance the utility of devices of that type to which the invention appertains.

10 With the above and other objects in view which will appear as the description proceeds, the invention resides in the combination and arrangement of parts and in the details of construction hereinafter described 15 and claimed, it being understood that changes in the precise embodiment of the invention herein disclosed, may be made within the scope of what is claimed, without departing from the spirit of the invention.

20 In the drawings:

Figure 1 shows in elevation, a device constructed in accordance with the invention, mounted on a building which appears for the most part in section;

25 Figure 2 is a section on the line 2—2 of Figure 1;

Figure 3 is a section on the line 3—3 of Figure 1, the door being open;

30 Figure 4 is a section similar to Figure 2, the door being open;

Figure 5 is a view similar to Figure 3, the door being closed.

The device forming the subject matter of this application may be used in connection 35 with a closure of any desired kind, and may be made in rights and lefts, as occasion may demand, this being a detail lying well within the skill of a mechanic instructed by the present disclosure. In order to avoid use- 40 less repetition, however, it will be supposed that the device is used to operate a garage door, and the description will proceed accordingly, without prejudice to the invention.

45 The numeral 1 marks the frame of a garage to which a door 2 is hinged at 3. An angle bracket 4 is secured to the inner surface of the door 2 and the horizontal flange of the angle bracket has an upstanding stop 5. One 50 end of a link 6 is pivoted at 7 to the hori-

zontal flange of the angle bracket 4. A carrying plate 8 is secured to the underside of the lintel 9 of the door frame. A lever 10 is connected at one end, by means of a fulcrum member 11, to the carrying plate 8. 55 The numeral 12 marks a retractile spring. One end of the spring 12 is joined by an anchor 14 to the carrying plate 8, and the spring can swing on the anchor 14. A connection 15 joins the opposite end of the spring 12 with the intermediate portion of the lever 10. The link 6 is offset as shown at 16, to accommodate the spring 12. A pivot element 17 joins one end of the lever 10 to the intermediate portion of the link 6. The link 6 is provided at its end with an upstanding detent pin 18 adapted to be received in a seat or notch 19 formed in one edge of the lever 10. A connection 20, such as an angle bracket, is pivoted at 21 to the link 6. A flexible element 22 is joined at one end to the connection 20. The flexible element 22 is passed through a pulley block 23 mounted on one of the door posts of the frame 1, or elsewhere, the flexible element 22 being extended downwardly from the pulley block 23 within reach 70 of an operator. When the door 2 is closed, the lever 10 is disposed above the link 6 in substantial alinement, vertically, with the link, the link being drawn over against the stop 5, by the action of the spring 12. If the flexible element 22 be drawn upon, the lever 10 will be swung, and after the connection 15 is carried past a line extended through the fulcrum member 11 and the anchor 14, the 75 spring 12 will tend to open the door, motion being transmitted to the door by way of the link 6. When the door 2 is open, as shown in Figure 3, the detent pin 18 on the link 6 is received in the notch 19 of the lever 10, then the parts 18 and 19 constitute inter- 80 engaging elements which limit the relative swinging movement of the lever 10 and the link 6 in one direction, as the door 2 is opened. The relative swinging movement between the lever 10 and the link 6, when the door is 85 closed, is limited by the engagement between the link 6 and the stop 5. Owing to this last described engagement (between the members 90 6 and 5) the door 2 will be stopped in a closed 95 100

position without using stop strips or other abutments on the door frame. Moreover, owing to the engagement between the parts 6 and 5, the lever 10 and the link 6 project 5 from the door 2 in a position at right angles thereto, when the door is closed, and if desired, the device may be operated to open or close the door, by taking hold of the end 24 of the link 6. The flexible element 22, therefore, 10 may be omitted in some cases, depending upon the particular structure wherewith the device is assembled.

What is claimed is:—

15 In a device of the class described, a frame, a closure hinged to the frame, a link pivoted to the closure, a lever pivoted to the link, means for fulcruming the lever on the frame, said means including a pivot on which the lever swings, interengaging elements on the 20 link and on the lever, cooperating to hold the link and the lever unfolded and in approximate alignment to form a rigid brace which holds the closure positively in an open position until the folding of the lever and the 25 link is begun, the lever and the link being foldable into approximate alignment and into a position approximately at right angles to the closed closure, and into such relation with respect to the pivot element as to hold 30 the closure closed positively until the unfolding of the link and the lever is begun.

In testimony that I claim the foregoing as my own, I have hereto affixed my signature.

ARCHIE CARL COOPER.
